NEEDLE THREADER

Carl A. Carlson, San Francisco, Calif.

Application February 4, 1935, Serial No. 4,788

1 Claim. (Cl. 223—99)

My invention relates to means for assisting in threading sewing needles of the common type, usually comprising a relatively small shank pierced adjacent one end for the reception of a thread. Customarily the needle eye is elongated and, in the case of sewing machine needles, is located within a longitudinal groove. It is an old expedient to insert a wire loop through a needle eye and to engage a thread with such inserted loop and then to withdraw the loop from the needle eye in order to pull the thread therethrough. Such an operation, however, is rather difficult with installed sewing machine needles and is likewise somewhat difficult with relatively small hand needles, since it is about as hard to insert the wire loop into the needle eye as it is directly to insert the thread therein.

It is therefore an object of my invention to provide a needle threader which increases the certainty of threading the needle and reduces the optical and physical difficulty of inserting a wire loop into the needle eye.

A further object of my invention is to provide a durable and simple structure for facilitating the threading of needles.

Another object of my invention is to provide a needle threader which is especially applicable for use in threading sewing machine needles.

The foregoing and other objects are attained in the embodiment of the invention as shown in the drawing, in which—

Fig. 1 is a plan, portions being in section, of a needle threader in accordance with my invention, showing a needle in position to be engaged thereby.

Fig. 2 is a plan similar to Fig. 1, but showing a needle farther engaged with my needle threader.

Fig. 3 is a view similar to Fig. 1 with the needle fully engaged with the threader and with the thread in initial position.

Fig. 4 is a view comparable to Fig. 1 but showing a succeeding step in the threading operation.

Fig. 5 is a view similar to Fig. 1 but showing substantially the final step in the threading operation.

Fig. 6 is a cross-section the plane of which is indicated by the line 6—6 of Fig. 1.

Fig. 7 is a cross-section the plane of which is indicated by the line 7—7 of Fig. 3.

Fig. 8 is a cross-section the plane of which is indicated by the line 8—8 of Fig. 4.

Fig. 9 is a front elevation of a portion of a sewing machine showing a modified form of the

needle threader of my invention in conjunction therewith.

Fig. 10 is a cross-section the plane of which is indicated by the lines 10—10 of Fig. 9.

In its preferred form the needle threader of my invention comprises a wire loop which is deformable to pass through the eye of a needle and with which is arranged a guiding or supporting plate for assisting in spacing and locating the needle through the eye of which the loop is to pass.

Although the needle threader of my invention is capable of various modifications in accordance with its particular field of use, it is well exemplified herein as including a wire loop 6. The wire 15 is of relatively small diameter and is somewhat flexible. It is formed into a substantially diamond-shaped figure, having a relatively small bend 7 adjacent one end, and then enlarging and diverging to a central portion 8 of maximum 20 spacing and then converging to bends 9 and 11 which terminate in oppositely disposed spaced portions 12 and 13 in substantial alignment. The bend 7 is of sufficiently small compass as to pass 25 easily through the elongated eye 14 of a needle 16.

In order that the relative location of the needle 16 and of the bend 7 can be readily maintained, I provide in accordance with my invention a needle-supporting plate 21 which is preferably a generally planar rectangular structure, 30 composed of strip metal. The plate is arranged in substantial parallelism with the plane of the loop 6 and is spaced therefrom approximately the distance from the exterior surface of the needle to the center of the eye 14 thereof, as shown 35 in Figs. 6 to 8 inclusive. In order that the plate 21 can be effectively maintained in co-operating relationship with the loop 6, I provide a turned-over portion 22 on the strip which is also folded upon itself, as at 23, to tightly overlie the portions 12 and 13 of the loop, which pass through an aperture 24 in the bent portion of the plate. When the overlapping parts of the plate are tightly pressed against each other, the ends 12 and 13 of the loop are firmly anchored with the 45 loop held in the desired relative location.

In the use of the structure as shown in Fig. 1, the needle 16 is brought into abutting relationship or into contact with the supporting plate 21, and then by a movement toward the left in 50 Fig. 2, sliding upon the supporting plate 21, the eye 14 of the needle overrides the loop 7, and, being further pressed toward the left, partially collapses the loop 6 until such time as the needle passes over the divergent portion 8 thereof and 55

- comes to rest substantially against the folded portion 23. Since the loop is then free again to expand it is ready for the reception of a thread 27. To accommodate the thread in the expanded portion 8 of the loop, I preferably pierce the plate 21 to provide an aperture 28 of relatively large size, readily to accept the thread 27 which is passed through the loop adjacent the region 8 and likewise through the aperture 28. 5
- 10 At this juncture the needle 16 is moved toward the right, as shown in Fig. 4, and, in again contracting the loop and passing off the bend 7 thereof, engages the thread 27 which is looped through the needle eye 14, as shown in Fig. 4. 15
- 15 Further movement toward the right in Fig. 5 of the needle 16 causes the end 29 of the thread to pull out from the needle eye 14 and ultimately to disengage itself from the bend 7, leaving the needle threader in its original condition and 20 leaving the needle 16 suitably threaded with the thread 27 passing through the needle eye. These movements are particularly well illustrated in Figs. 6 to 8, wherein is shown the effect of the needle-supporting and guide plate 21. 25
- 25 This supporting plate and the relationship thereof with the needle are especially valuable in threading sewing machine needles, for example as shown in Fig. 9. Since the needle in this instance is not readily movable, and since the 30 thread must ordinarily do all of the maneuvering for entering into the needle eye, and since

the needle 31 customarily is provided with a longitudinal groove 32, it is relatively simple ordinarily to move the plate 21 behind and slightly overlapping the needle 31 and then to bring it forward until it comes into contact with the 5 needle. It is then necessary simply to move the plate to the left, as shown in Fig. 9, until the bend 7 engages with the longitudinal groove in the needle and then to slide the entire structure relatively downward until such time as the bend 10 7 engages with the needle eye and can be translated toward the left in Fig. 9 to follow the same sequence of operations as illustrated in the preceding figures.

If desired, the surface of the plate 21 can be 15 coated, or a separate celluloid sheet 33 can be clamped in the fold 34 in order to provide a contrasting background for the loop 6 and the needle. In the latter case, the metal 21 can be additionally pierced as at 36 to admit light to 20 the translucent sheet 33 to silhouette the loop and the needle.

I claim:

A needle threader comprising a wire loop having a central, relatively open part and a terminal bend, and a plate fastened to and underlying said loop, said plate having a first aperture therein underlying said central part of said loop and having a second aperture therein underlying said bend in said loop. 25
